DESIGN FOR A COMBINED ESCUTCHEON PLATE AND CRYSTAL FOR A DIAL FOR A RADIO RECEIVER

Richard C. Marholz, Chicago, Ill., assignor to
Belmont Radio Corporation, Chicago, Ill., a
corporation of Illinois

Application October 20, 1937, Serial No. 72,341

Term of patent 7 years

To all whom it may concern:

Be it known that I, Richard C. Marholz, a citizen of the United States, residing at Chicago, in the county of Cook and State of Illinois, have invented a new, original, and ornamental Design for a Combined Escutcheon Plate and Crystal for a Dial for a Radio Receiver, of which the following is a specification, reference being had to the accompanying drawing, forming part thereof, in which:

Figure 1 is a front view of my design for a combined escutcheon plate and crystal for a dial for a radio receiver, and

Figure 2 is a side elevation thereof.

I claim:

The ornamental design for a combined escutcheon plate and crystal for a dial for a radio receiver, as shown.

RICHARD C. MARHOLZ.
